UNITED STATES PATENT OFFICE.

JOSEPH M. ERTS AND JOHN MILLER, OF POUGHKEEPSIE, NEW YORK.

GAS-HOLDER.

SPECIFICATION forming part of Letters Patent No. 637,101, dated November 14, 1899.

Application filed April 17, 1899. Serial No. 713,380. (No model.)

To all whom it may concern:

Be it known that we, JOSEPH M. ERTS and JOHN MILLER, citizens of the United States, residing at Poughkeepsie, New York, have invented certain new and useful Improvements 5 in Gas-Holders, of which the following is a specification.

Our invention relates to improvements in the generation of acetylene gas; and the object of the invention is to provide an improved 10 form of holder for receiving the gas.

The invention is illustrated in the accompanying drawing, in which the figure represents a central vertical section through the 15 holder.

Referring to the drawing, A represents the water-chamber, in which the gas is generated, and B the gas-holder for the storage of the 20 gas.

We divide the bell into two chambers C and D by a vertical diaphragm b, which extends below the water-line and forms two chambers.

The inlet-pipe E from the generator extends into one of these chambers, and the outlet-pipe extends from the other. An opening 25 through the diaphragm above the water-line is closed by a filtering material e, which serves to effectually prevent the passage of impurities. The bell preferably carries a rack F, which meshes with a gear G, operating a suitable carbid-feed, whereby the rise and fall of the bell controls the feed of the carbid. 30

We claim as our invention—

A bell having a transverse partition forming inlet and outlet chambers, and a filtering 35 material occupying an opening in said partition, substantially as described.

In testimony whereof we affix our signatures in presence of two witnesses.

JOSEPH M. ERTS.

JOHN MILLER.
